TAIN G. McDUGAL, OF FLINT, MICHIGAN, ASSIGNOR TO CHAMPION IGNITION COMPANY, OF FLINT, MICHIGAN, A CORPORATION OF MICHIGAN.

BURNING CERAMIC WARES AND APPARATUS THEREFOR.

1,416,726.

Specification of Letters Patent. Patented May 23, 1922.

Continuation of application Serial No. 329,705, filed October 10, 1919. This application filed July 13, 1921. Serial No. 485,784.

To all whom it may concern:

Be it known that I, TAIN G. McDUGAL, a citizen of the United States, and a resident of Flint, county of Genesee, and State of Michigan, have invented certain new and useful Improvements in Burning Ceramic Wares and Apparatus Therefor, of which the following is a full, clear, concise, and exact description, such as will enable others skilled in the art to which the invention relates to make and use the same, reference being made therein to the accompanying drawings, which form a part of this specification.

15 In the firing of clay wares as generally conducted, the burning takes place in large periodic units in which the wares are placed in saggers or fire-clay boxes that are stacked up anywhere from ten to thirty or more 20 high, depending on the height of the particular ware. For the cruder wares such as bricks, the furnace or kiln is usually rectangular, whereas for dish-ware and porcelain and other products of a better class the 25 kiln is round and of from eight to thirty or more feet in inside diameter.

Because it is necessary to heat so large a mass of material from normal temperatures to the temperature required to properly bake 30 or vitrify the ware, it is necessary:

1. That these large units be burned at a very slow rate in order to insure the proper even distribution of heat throughout the great mass. From 24 to 144 hours are 35 required to complete a cycle consisting of placing ware in the kilns, raising the heat slowly to the proper temperature, holding at this temperature until the whole mass is uniformly heated, cooling the large mass, and 40 finally emptying the oven.

2. That a loss be expected and provided for on account of over-fired and under-fired ware due to uneven heat distribution throughout the large mass.

45 3. To provide and maintain a department for manufacturing saggers which have an average life of four or five successive burns. These saggers are necessary to allow the ware to be stacked in the ovens, and also to 50 protect it, in the case of coal fuel being used, from the dirt in the combustion gases. In the case of all fuels the saggers also afford a protection for the ware from too sudden heat directly in front of the spaces

through which the combustion gases enter 55 the kiln.

4. To employ labor to enter hot chambers of the kiln for unloading and loading the saggers of ware.

For the purpose of eliminating the difficulties inherent to the use of periodic kilns, a continuous process has been developed heretofore which provides for the placing of the saggers or fire-clay slabs upon a refractory car-top and passing the cars through a tunnel from three hundred feet to six hundred feet long, comprising a pre-heating, a high-temperature, and a cooling zone. With this method the saggers or slabs which support the ware are piled in mass four to eight feet 70 high on the cars, which travel the length of the tunnel-kiln in not less than twenty-four hours. This method of mass-burning, while it eliminates the necessity of workmen entering the kiln for loading and unloading purposes, and while it reduces the time of firing somewhat, is nevertheless subject to the loss incident to over-firing and under-firing growing out of the uneven distribution of heat, especially from top to bottom of the 80 mass, and to the expense of forming and handling the saggers.

A leading object of the invention is to provide for both a more rapid and a more uniform burning of the ware than has been 85 attained heretofore, whereby the quality of the goods is improved and the percentage loss incident to even the most approved prior practice is substantially avoided. To this end it resides in an improved method for 90 burning ceramic wares or silicate bodies in a kiln of the continuous type, said method consisting in exposing them openly, preferably while in a single tier only, to the intense heat of a substantially flameless combustion 95 of pre-mixed air and fuel directed against the closely adjacent top or dome of the kiln and reflected thereby down onto the ware. In this manner the individual articles are each subjected to the direct intense heat of 100 say 2300° F. or thereabouts to 2650° F. or possibly higher, as distinguished from the previous practice of piling in mass either with or without saggers; and the time necessary for firing is reduced from twenty- 105 four hours or more in the case of spark plug porcelains to as low as six hours or even less, and a more uniform grade of product is se-

cured. In connection with articles such as small floor tile, the temperature may be somewhat lower than stated heretofore.

Again, certain ceramic mixtures of more recent development, which require very rapid and careful cooling to prevent crystallization of the porcelain to an extent sufficient to render it worthless for spark plug insulators, possess, when properly burned and cooled, exceptional toughness coupled with highly desirable electrical properties; these mixtures have not heretofore gone into extensive use for the reason that no process or means was available by which they could be economically produced.

The invention further consists in a process whereby wares formed of mixtures having these characteristics may be produced on a commercial scale, said process consisting in passing the articles through a continuous kiln in the manner stated in the preceding paragraph at a speed such that the cooling takes place in less time than would enable the formation of the objectionable crystalline structure. The equivalent of this process could not be attained with the wares stacked up in saggers for the reason that the necessary rapid and uniform cooling could not then be attained, but by exposing the wares in single tier formation all cool quickly and at substantially the same rate.

Again, the invention consists in a continuous kiln of the type set forth wherein the ware is placed directly on the upper surface of the car or other carrier or in open trays as distinguished from saggers, which latter are so designed that they may be placed one on another to form enclosed spaces from which the combustion gases are more or less excluded, and in which spaces cooling is more difficult and less efficient.

The invention also provides trays or other ware supports, the only permanent sides of which are positioned along the outer side of the car or carrier to prevent the spark plug porcelains or other wares being treated from falling off, the other sides of the tray or support being preferably provided with temporary retaining strips of metal or of some combustible material such as cardboard, whereby the ware is prevented from falling off when the trays are being handled prior to being placed on the cars or other carriers. In this manner an increased carrying surface is secured and the wares, particularly when small, are more fully exposed to the direct heat.

A further important object is to enable the heating and cooling steps to be effected at an increased rate as compared with that necessitated by the use of cars on which both the wares and a large mass of refractories are necessarily carried. While this may be accomplished in various ways, I prefer to

form the ware-supports as thin slabs or trays of highly refractory material which themselves ride on suitable conveyor-elements of heat resisting and insulating material, the necessary body or backing of fire brick and insulating brick (heretofore carried on the cars) being stationary. In this manner the very large quantity of heat necessarily wasted in the cooling of the large moving mass of the kiln as heretofore constructed is saved, and the time element incident to heating up and cooling down is further reduced.

An additional object is to prevent the current of air to which the wares are preferably finally subjected for cooling from passing into the highly heated zone of the kiln, this being accomplished by means of a movable baffle which conforms to the upper surface of the carrier without interfering with the passage of the wares.

As stated heretofore, the present invention differs from prior practices in that mass-firing is avoided, and for this purpose the wares are placed on the movable car tops, trays or other carriers in a single open tier or so arranged as to be directly subjected to the downward radiation or reflection of heat from the over-lying arch wall of the tunnel, this wall being in turn intensely heated by blasts from burners wherein air and gas fuel or air and oil are pre-mixed in the proper proportion to produce substantially flameless or surface combustion, that is, wherein there is substantially no excess of either air or fuel, or wherein a small excess of oxygen is admitted for the purpose of burning out organic matter contained in the raw porcelain. The articles, for example spark plug porcelains, are thus subjected directly to the intense heat and vitrify substantially uniformly without the loss, or variation in product incident to the previous continuous kiln practice. Such spark plug insulator compositions as require it may be subjected to controllable neutral or reducing atmospheres for the purpose of developing finished structures best obtained under such conditions.

In the manufacture of certain small articles, such, for example, as thin units of mosaic tile flooring, butter pats, saucers, plates, etc., it is found that the article may be stacked in more than one layer or tier, and that if properly piled to allow direct application of the heat in the high-temperature zone the desirable effects resulting from the invention are obtained. Adjacent units may actually be arranged in contact one with another when green or unfired, as the case of mosaic tile elements referred to above, the exposure necessary in the hot zone resulting from the shrinking in the pre-heating zone, provided, of course, that the articles be piled one directly above the

- other so as to form vertical columns, (or otherwise piled in such manner that the several sides of the articles are exposed) these individual columns in effect being the same as the individual porcelains more particularly shown in the drawings. It is evident that the multiple tier formation so defined is nothing more or less than a modification of the single tier open formation.
- 10 Applicant believes himself to be the first to employ the open small mass formation, as distinguished from the usual closed or protected mass formation; the absence of anything in the nature of saggers or other kiln refractories interposed between the source of heat and the wares to be fired, together with the continuous nature of the furnace, permits direct application of the heat and gives rise to results and economies 15 not heretofore attained.
- In the drawings, Figures 1 and 1^a are central vertical longitudinal sections each showing substantially one-half the length of the kiln, Figure 1 being at the charging end;
- 20 Figures 2, 3, 4 and 5 are sections on the lines 2—2, 3—3, 4—4 and 5—5, respectively, of Figure 1;
- 25 Figure 6 is an enlarged vertical transverse section showing the article retaining sides or elements of the trays which are preferably used when the latter are of less width than the carrier;
- 30 Figure 7 is an enlarged vertical section through the adjacent end portion of two of the cars appearing in Figure 1, showing the preferred manner of placing the trays thereon to prevent the combustion gases from gaining access to the iron wheels and other 35 parts; and
- 35 Figure 8 is an enlarged transverse cross-section showing a modified construction whereon the wares are carried.
- The actual construction of the kiln is subject to considerable variation. As shown in Figures 1, 1^a, 2, 3, 4 and 5, it is built up on a concrete foundation 1 whereon are supported suitable tracks or the equivalent 2 along which the cars 3 are slowly moved 40 from left to right, Figures 1 and 1^a, by suitable propelling means, not shown. To seal the joints between the brickwork 4 and the cars, the former is extended inwardly to form ledges 5 beneath which sand boxes 6 45 are provided, as by means of the angle irons 7, and the cars are equipped with depending plates 8 that drag in the sand. The car bodies conform fairly closely to the walls, including the ledges 5, so that but little space 50 exists through which the sides of the car are subjected to heat.
- 55 It will be seen that the kiln comprises three zones, namely, a pre-heating zone, a high-temperature zone, and a cooling zone.
- 60 65 The pre-heating zone is preferably provided with a series of overhead baffles 9 which reach down nearly to the wares on the cars and thereby divide the structure up into a plurality of chambers 10, 10', 10'', etc., in which the temperature increases from left to right, Figure 1. A suitable outlet 12, that may be closed by a damper or slab 13, is provided for the waste gases. The temperature of the wares and cars is thus gradually raised in the pre-heating zone to a point where they will safely withstand the highest temperature available, whereupon they pass into the high-temperature zone.
- Both walls of this zone are provided throughout their length with upwardly and inwardly inclined passages 15 directed substantially toward the longitudinal mid-line of the tunnel dome or arch 16, which is here formed of material of the highest refractory nature; and through these passages gaseous or oil fuel and air pre-mixed in substantially such relative proportions that there is enough air, and practically no more than is required to completely burn the fuel is directed in blasts which may easily be made to maintain the dome substantially white hot in the event spark plug porcelains are being treated, or at a lesser temperature when such is desirable by reason of the nature of the ware, as in the case of enameling or coating iron ware. This "flameless" combustion generates unusually high heat in an exceedingly small space and has substantially no coloring influence on the ware, although the latter is fully exposed.
- 70 From the high-temperature zone, the cars pass closely under the flat lower surfaces of a baffle arch or space made up preferably from highly refractory blocks 20 of carbonitride or the like backed by some 75 cheaper insulating filling 21, whereupon they emerge into an area in which they are subject to indirect cooling brought about by a circulation of air through the kiln walls, preferably in the manner best indicated in Figures 1^a and 4. As shown therein, the air is admitted to the interior of the tunnel wall through a passage 23 and from there flows 80 upwardly, transversely across the kiln, and downwardly, back and forth in a series of 85 passages, or rather in a continuous passage 24 that leads toward the highly-heated zone and communicates with a stack 25. In this manner the coolest portion of the air current 90 is opposite the cooler portions of the tunnel which tends to prevent warping and cracking of the walls. The moving cars next enter a water cooled section of the tunnel 95 wherein water is circulated through suitable piping 28 disposed just above the level of the wares, the flow preferably taking place 100 toward the middle of the tunnel. In this manner the wares are very gradually and definitely cooled down and might in some instances then be removed immediately from 105

the kiln, but it is preferred to continue the cooling process through the medium of an extension chamber or jacket 30 to which air is supplied by means of the pipes 31. It 5 will be understood that the construction of the cooling zone is subject to considerable variation.

As is best indicated in Figure 6, the wares, particularly when in the form of small articles such as spark plug insulators 35, are set up on end preferably on trays 36 of highly refractory material which are then placed upon the cars 3. In order to secure a maximum effective carrying space and a 15 full exposure of the articles to the direct heat, it is preferred to provide the ribs 37 only on one side of the trays, and to prevent the articles from falling off the other three sides, when the trays are being handled, by 20 means of suitable thin retainers such as the rectangular loop 39, one edge of which fits over the rib 37. When these loops are made of card-board or the like they burn away and leave the porcelains fully exposed; if 25 constructed of metal they are removed after the trays have been placed on the cars or conveyor and before the car or conveyor enters the kiln. By allowing the trays of one car to bridge the joint between it and 30 the next, the combustion gases are prevented from passing down about the wheels and other iron work of the car and kiln. The joint may be further sealed and the refractories relieved of direct pressure on one another by facing the joint, preferably along 35 its lower edge, with an asbestos rope or the like 40 secured to one of the cars in any suitable manner; for example, each car may be provided with an angle facing 41 to one or 40 both of which the rope facings may be attached.

In order to prevent the air which enters through the pipes 31 from passing into the hotter portion of the kiln, I preferably provide 45 a baffle plate 42, Figure 1^a, pivoted at 43 and having its lower edge arranged to drag over the porcelains as they pass into the air cooled space.

It will be observed that the cars 3, which 50 may be of the conventional type, necessarily include, as a protection for the wheels and other metal work thereof, a large mass or body of refractory and insulating material which must be heated up and cooled down at 55 each passage of the car through the kiln, thereby causing costly losses both in time and heat. In order to effect a saving in these particulars, I preferably construct the kiln in the general manner shown in Figure 60 8, wherein 50 indicates suitable conveyor elements—as shown, rollers—constructed of refractory material such as silicon carbide, zirconium compounds, corundum, etc., upon which the thin refractory carriers or trays 65 51, also preferably of the same materials,

are carried, it being understood that there are a series of such rollers spaced from each other longitudinally of the tunnel distances considerably less than the length of the carriers. The floor of the tunnel is built in 70 close to the over-hanging sides of the trays and between the lines of conveyor elements with fire brick and insulation brick or material 52—53, so that the heat which would pass into a car body of the conventional type 75 is absorbed by the stationary mass and made use of to heat up the thin on-coming refractory slab or tray. In this connection, it will be understood that the drop in temperature through the tray or carriers 50 is relatively 80 small, the temperature immediately beneath the carrier being too high to permit the use of metal rollers in the high heat zone especially, although metal rollers or conveying mechanism could be employed in parts of 85 the pre-heating and cooling. In the construction shown, the refractory rollers are of sufficient diameter to protect the shafts 54 on which they are secured, and the latter extend outside the furnace to lubricated 90 bearings 55. By forming the carriers or trays and the wheels with associated bearing and guiding surfaces 56—57, the former are guided properly from end to end of the kiln. Obviously, the rollers may either be 95 of the driven or of the free running type, in which latter case any suitable means for pushing or propelling the slabs may be provided. Again, while I have shown the refractory conveyor elements in the form of 100 rollers, it is clear that heat insulating conveyors of different construction, such, for example, as the reciprocating or step-by-step type, might be used.

From the foregoing it will be understood 105 that the wares in all cases travel through the kiln continuously from end to end whether the movement be constant or step-by-step, and it is in this sense that the term "continuously" is employed in some of the 110 claims.

This application is a continuation of my application for United States Letters Patent Serial No. 329,705, filed October 10, 1919.

I claim:

1. That improvement in the art of burning ceramic wares which consists in continuously passing said wares through a kiln having a pre-heating zone, a high-temperature zone and a cooling zone, and maintaining 120 said wares openly exposed to radiation from the under surface of the ceiling of the kiln in the high-temperature zone for a period sufficient to insure thorough burning throughout the whole mass of said wares, 125 said under surface being intensely heated by combustion in the space between it and the wares.

2. That improvement in the art of burning 130 ceramic wares which consists in slowly

- passing said wares through a continuous kiln while exposed openly in single tier formation to the direct action of the intense heat of substantially flameless combustion 5 of pre-mixed air and fuel and maintaining said wares in the high-temperature zone for a period sufficient to insure thorough burning throughout the whole mass of said wares.
- 10 3. That improvement in the art of burning small ceramic wares which consists in passing said wares, while openly exposed to radiation, through a continuous kiln embodying a high-temperature zone having a 15 dome immediately above and closely adjacent the wares, the under surface of said dome being intensely heated by combustion in the chamber through which said wares pass, and maintaining said wares in the 20 high-temperature zone for a period sufficient to insure thorough burning throughout the whole mass of said wares.
4. That improvement in the art of burning ceramic wares which are susceptible to 25 the formation of objectionable crystalline structure on slow cooling, which consists in passing said wares through a continuous kiln having a pre-heating zone, a high-temperature zone and a cooling zone, the time 30 during which the passage of the wares through the cooling zone is effected being less than the period for the formation of said objectionable crystalline structures.
5. In a continuous arched kiln for burning 35 ceramic wares, a car arranged to travel through the kiln, and having a body of heat insulating material, a thin substantially flat tray of highly refractory material resting on said body and freely removable therefrom to 40 permit positioning of the wares in a single tier thereon, while the tray is detached from the car, said wares when so positioned being open, both on top and at the sides, to the direct action of heat reflected from the dome 45 of the kiln and exposed to direct contact with the combustion gases as they travel toward the charging end of the tunnel.
6. In a continuous kiln for burning ceramic wares, a car arranged to slowly travel 50 through the kiln, and having a body of heat insulating material, a thin substantially flat tray of highly refractory material resting on said body and freely removable therefrom to 55 permit positioning of the wares in a single tier thereon, the trays being provided with thin low edges whereby the wares are prevented from falling off as the trays are placed on the cars.
7. In a continuous kiln for burning ceramic wares, a series of cars arranged to 60 travel through said kiln from end to end, said cars including bodies of heat insulating material each spaced somewhat from the bodies of the adjacent cars, and thin low 65 trays of highly refractory material resting
- on said bodies and overlapping the spaces therebetween, said trays forming supports for the wares.
8. In a continuous kiln having a pre-heating zone, a high-temperature zone and a 70 cooling zone, the latter including a section through which air is circulated, means movable through the kiln for carrying wares being burned therein, and a swingable baffle tending to shut off communication between 75 said section and the rest of the cooling zone and having its free edge movable with the movement of the carrying means to permit the passage of the latter thereunder.
9. That improvement in the art of burning 80 ceramic wares which are susceptible to the formation of crystalline structure on slow cooling, which consists in passing said wares through a continuous kiln having a pre-heating zone, a high-temperature zone, and 85 a cooling zone, the time during which the passage of the wares through the cooling zone is effected being such that the formation of said crystalline structures is regulated by a pre-determined manner. 90
10. That improvement in the art of burning ceramic wares which consists in continuously passing said wares while openly exposed to radiation through the high-temperature zone and the cooling zone of a kiln, the 95 high-temperature zone having a dome below which said wares pass in close proximity thereto, said dome being intensely heated by heat generated between it and said wares, said kiln also having a pre-heating zone 100 through which said wares are passed before entering the high-temperature zone.
11. That improvement in the art of burning small ceramic wares which consists in slowly passing said wares through an arched 105 continuous kiln and immediately below the arch of said kiln while said wares are openly exposed to downward radiation from said arch and while the under surface of the latter is exposed to the direct application of heat 110 of an intensity at least as great as that of substantially flameless combustion of pre-mixed air and fuel.
12. That improvement in the art of burning small ceramic wares which consists in 115 passing said wares, while separated from the laterally adjacent wares so as to be openly exposed to radiation, through a continuous kiln embodying a high-temperature zone having a dome immediately above and 120 closely adjacent the wares, the under surface of said dome being intensely heated by combustion which occurs substantially wholly in the space immediately underneath said surface, and maintaining said wares in 125 the high-temperature zone for a period sufficient to insure thorough burning throughout the whole mass of said wares.

In testimony whereof I affix my signature.
TAINE G. McDUGAL.
